UNITED STATES PATENT OFFICE.

GEORGE G. F. BOSWELL, OF INDIANAPOLIS, INDIANA, ASSIGNOR OF ONE-FOURTH TO
DAVID A. BOSWELL, OF INDIANAPOLIS, INDIANA.

COIN-CONTROLLED LOCK.

1,031,833.

Specification of Letters Patent.

Patented July 9, 1912.

Application filed November 13, 1911. Serial No. 660,107.

To all whom it may concern:

Be it known that I, GEORGE G. F. BOSWELL, a citizen of the United States, and a resident of Indianapolis, county of Marion, and State of Indiana, have invented a certain useful Coin-Controlled Lock; and I do hereby declare that the following is a full, clear, and exact description thereof, reference being had to the accompanying drawings.

The object of this invention is to provide a coin controlled lock of improved construction and one which can be readily reversible and adapted for use on either of the lateral edges of either side of a door.

The invention is particularly adapted for use on booths and the like.

So far as known the jobber or dealer of any of the coin controlled locks now on the market, must carry four styles of the same lock, that is, right and left hand locks for use on both the inside and outside of a door. The use of this lock will obviate this difficulty besides presenting other novel features.

The nature of the invention will be understood from the accompanying drawings and the following description and claims.

In the drawings, Figure 1 is a side elevation of the portion of a door with the device installed thereon. Fig. 2 is a front elevation of the same. Fig. 3 is a vertical transverse section on the line 3—3 of Fig. 2, and before the bolt has been withdrawn. Fig. 4 is a view similar to Fig. 3, but with the bolt withdrawn. Fig. 5 is a section on the same line as for Fig. 3, but looking in the opposite direction. Fig. 6 is a front elevation of the upper part of the lock with the casing removed. Fig. 7 shows the same as Fig. 6, but with portions broken away and with the bolt withdrawn under the action of the front knob shaft. Fig. 8 shows the same as Fig. 7, but with the bolt withdrawn by the action of the rear knob shaft. Fig. 9 is a horizontal transverse section on the line 9—9 of Fig. 7. Fig. 10 is a front elevation of the upper portion of the lock with the casing removed and showing the parts associated to work upon the door of a different hand from that shown in Figs. 6, 7 and 8. Fig. 11 is a horizontal transverse section on the line 11—11 of Fig. 10. Fig. 12 is a section similar to that of Fig. 11, but with the bolt inverted. Fig. 13 shows the method of closing the idle

bolt hole. Fig. 14 is a detail of the front knob shaft. Fig. 15 is a perspective of the slot closing or indicator plate in an inverted position.

In detail there is shown in the drawings, 60 a portion of a door 10 with a coin controlled lock thereon having a casing 11, front knob 12, rear knob 13 and bolt 14, which is withdrawn by dropping a coin through a slot 15 in the upper part of the face of the casing 11 and turning the knob. The upper part 65 of the casing 11 surrounds the lock mechanism, while the lower portion serves as a coin receptacle to which access may be had through a door 16 in the casing 11 and 70 which is locked by means of a small key lock 17. There is a rear plate 18 secured to the door to which the casing 11 is secured by means of screws 19 and upon which plate 75 the various parts of the lock mechanism are mounted. There is a plate 20 extending transversely of the rear plate 18 and extending outwardly therefrom upon which the bolt 14 rests. The bolt 14 is substantially H-shaped in cross section, as shown 80 in Figs. 3 and 4, and at one end 21 the legs are substantially longer than for the rest of the bolt, see Figs. 9 and 11. There is an Italian-cross shaped slot through the bolt 85 with the nave 22 parallel with the rear plate 18 and the transept 123 extending at right angles thereto and within the enlarged portion 21 before mentioned. The nave portion extends for substantially the entire length of the bolt which is normally within the casing 10, and the transept portion extends for 90 substantially the length of the legs of the H-shaped portion 21. The end of the bolt extending beyond the casing 10 is tapered 95 as usual in lock constructions, and near such tapered end but within the casing there are upwardly and downwardly extending projections 122 whose ends lie parallel with the ends of the H-shaped portion 21. On the upper face of the bolt 14, a 100 groove 23 is cut which extends through that portion of the bolt which lies within the casing and on the lower face a groove 24 is cut which extends for the entire length of the bolt. The slots 23 and 24 with the remaining portions form the H-shaped portion, before mentioned. The transept portion 123 of the cross-shaped slot intersects the slots 23 and 24 and, for the purpose of 105 making a continuous slot on the side of the 110

- bolt adjacent the rear plate 18, a plate 25 is inserted and held by means of screws 26, as seen in cross section in Figs. 11 and 12. In Fig. 11 the plate 25 lies in the slot 24, while in Fig. 12, it lies in the slot 23, to meet the demands for locks on different doors. A spring 27, secured to a lug 28 on the rear plate 18, presses against the inner end of the bolt 14 and forces it outward.
- 10 Near the upper end of the rear plate 18 there are two inwardly and horizontally extending plates 29 which are joined at right angles to vertical plates 30 which are spaced apart and lie opposite the coin slot 15 in the casing 11, before mentioned, and form a coin chute which leads downward to a point adjacent the shaft 31 for the rear knob 18, as shown by dotted lines in Fig. 6. In normal position, the coin opening 15, the opening 32 in a slot closing plate 33, hereafter described, the coin chute 34, the slot 35 through the rear knob shaft 31, and the transverse portion 23 through the bolt 14, are in line. There is also a slot through the plate 20, heretofore mentioned, which is in line with the coin chute 34. There is a second slot 36, indicated by dotted lines in Fig. 6, to allow movement of an arm 37 on the front knob shaft sleeve 38. Said slot 20 lies parallel with the rear plate 18.
- 15 The slot closing or indicating plate 33 is formed of a rectangular plate, as shown in Fig. 10, having two vertically extending openings 32 which will register with the coin opening 15, and a horizontally extending opening 39 through which extends the rear knob shaft 31. On the rear side of the horizontal plate 33 there is a rearward projection 40 at the upper end which is adapted to rest upon the horizontal plates 29 from the rear plate 18 and thus support the slot closing plate 33, see Fig. 15. There are also rearwardly extending lugs 41 secured near the lateral edges of the plate 33 which are adapted to engage the stops 42 on the rear plate 18 and limit the side movement of the plate 33. At the lower end of said plate 33 and on the rear side also, a plate is secured which has a central slotted portion 44 with a downwardly and inwardly inclined portion 45 on either side and with the ends 46 turned at right angles to the plate 33 to form lugs which will be engaged by the coin, as hereafter described.
- 20 Said plate lies within the slot in the bolt 14 which is adjacent the casing 10. As shown in Fig. 11, these lugs 46 project within the slot 23, while in Fig. 12, said lugs project within the slot 24. In the normal position 25 of the lock with the bolt thrown, one of the slots 32 mates with the coin opening 15 and with the coin chute 34 and the inclined portion 45 lies opposite the transverse portion 123 through the bolt 14.
- 25 The front knob shaft is formed of two parts, an inner core 47 which has one bearing in the rear plate 18 and the other in the front knob 12 and an outer or sleeve portion 38 which has the projecting arm 37, before mentioned. That portion of the inner core 70 47 which lies within the casing is circular in cross section and has a longitudinal slot 48 central therewith. A pin 49 is inserted into the end of the cylindrical portion 75 which lies adjacent the casing 10 and fits within a slot 50 in the sleeve member 38, whereby said sleeve member is turned when the inner core member 47 is turned by the action of the knob 12.
- 30 The portion of the sleeve portion 38 which lies within the casing is substantially cylindrical and is annular in cross section and has slots 51 which mate with the slot 48 in the core 47. The arm 37 is secured to said cylindrical sleeve member 38, substantially 85 midway between the front and rear casings, said arm extending through the slot 36 in the plate 20 and normally lies within the nave portion 22 of the cross-shaped slot within the bolt 14, as shown by dotted lines 90 in Figs. 6, 7 and 8. A short link 52 is attached to said arm 37 near the sleeve and its outer end is caught by a flat spring 53 which is secured to the transverse plate 20 by a bolt 54 and serves to return the front 95 knob shaft members 38 and 47 to their normal position, as shown in Fig. 6. There is a slot 50 on each end of said sleeve 38.
- 35 As shown in Fig. 4, the inner end of the front knob 12 is threaded and an internally 100 threaded sleeve 55 which has one flange 56 is screwed onto the threaded end of the knob 12 so that said flanged end 56 bears against the inner side of the casing 11. Thus after the core 47 of the knob shaft is 105 inserted into the central slot 57 of the knob 12, it is impossible to remove said knob from the outside.
- 40 The inner knob shaft 31 has a bearing in the rearwardly extending sleeve 58 from the 110 rear plate 18 and that portion which lies within the casing is circular in cross section and has the central slot 35, which in normal position, lies opposite the coin chute 34. A bar 59 is secured to one side of said 115 knob shaft and lies against the rear plate 18 and the lower end thereof projects behind the bolt 14 in the slot formed by the lug 122, the rear plate and the enlarged end portion 21 of the bolt. The end of the knob 120 shaft adjacent the front casing is formed to receive a porter's key, which may be inserted through an opening 60 in a boss 61 in the front casing 10. When the key is so inserted, and turned, it will cause the lower 125 end of the bar 59 to bear against the inner end 21 of the bolt and against the plate 25 secured therein and move the bolt inwardly against the action of the spring 27 to the position shown in Fig. 8. The outer end of 130

the rear knob shaft has the rear knob 13 secured thereon by a construction very similar to that used for the front knob shaft 12.

For the purpose of adjusting the lock so that it may be used on a different door from that for which the lock shown in Fig. 6, was intended, the casing 11 is removed, after which the inner parts of the lock are removed. The rear knob shaft is then inserted in the position shown in Fig. 10, with the bar 59 on the opposite side of the vertical plates 29 from what is shown in Fig. 6. The bolt 14 is then inserted so that the tapered outer end extends to the right and the spring 27 is secured to the left-hand lug 28 instead of to the right-hand one, as shown in Fig. 6. The knob shaft sleeve 38 is removed from the core 47 and reversed so that the arm 37 will lie on the opposite side of the core 47 from the position shown in Fig. 6. The spring 53 is also moved from the left to the right hand side of the plate 20 and secured to the arm 37 by means of the link 52. The opening in the casing 11, through which the bolt 14 formerly extended, is now closed by means of a small plate 63 which lies on the outside of the casing, as shown by dotted lines in Fig. 13, and is secured by a spring 64 on the inside which bears against the walls of the casing and holds it securely.

With the parts of the lock in the positions, as shown in Fig. 6, where the bolt is thrown, a coin on being inserted through the coin opening 15, will pass through one of the coin slots 32 in the slot closing plate 33 into the coin chute 34 and fall downward and, passing through the central slot 35 in the rear knob shaft 31 will pass into the transept portion 123 of the cross-shaped slot in the bolt 14 and will be caught by the inclined portion 45 on the plate 33. The front knob, then being turned, the arm 37 on the sleeve 38, will engage the coin within the bolt and cause the withdrawal of the bolt against the action of the spring 27 and the coin, pressing against the inward projection 46 from the rear side of the slot closing plate 33, will move said slot closing plate to the right from the position shown in Fig. 6 to that shown in Fig. 7, and close the passageway from the coin slot 15 to the coin chute 34. The bolt being withdrawn, the door may then be opened. Upon the release of the front knob, the spring 53 will return the front knob shaft members to their normal position, as shown in Fig. 6, but the slot closing plate will remain in the position shown in Fig. 7, indicating to any one on the outside of the door that the booth is occupied. The occupant of the booth, upon leaving, by grasping the rear knob and turning the same, will move the rear knob shaft and associated parts to the position shown in Fig. 8, where the lower

end of the arm 59, is shown as having caused the withdrawal of the bolt 14 and the upper end of said arm has engaged one of the inward projections 41 on the slot closing plate 33 and pushed it to the left, again opening the passageway from the coin opening 15 through said plate 33 to the coin chute 34. Upon the releasing of the rear knob 13, the spring 27 will cause the bolt 14 to be thrown and such movement will move the arm 59 on the rear knob shaft 31 to its normal position, as shown in Figs. 6 and 7.

While there are many minor changes which may be made upon this lock, which will materially change its appearance, it is not thought that they will alter the nature of the invention and it is not desired to claim the exact features herein shown.

It will be noted that with this construction and method of securing a knob shaft, it is impossible to remove the knob shafts or to remove the lock itself from the door without unusual violence except by opening the front door.

In the drawings a counter has been shown as secured to the rear plate 18 and operated by a link from the slot closing plate 33, but this constitutes no important feature of the invention.

I claim as my invention:

1. A coin controlled lock including a casing with a coin chute, front and rear knob shafts, a bolt in the casing adjacent the knob shafts and formed so as to be reversed or inverted and having a transverse slot registering with the coin chute, and means actuated by said shafts for engaging the coin when in the bolt for operating the bolt, whereby the lock may be used for a right or left hand lock or on the inside or outside of a door as desired.

2. A coin controlled lock including a casing with a coin chute, a knob shaft through the casing with a coin opening through it registering with the coin chute, a reversible bolt adjacent said shaft and transversely thereof and with a transverse slot registering with a slot in the shaft, an extension from said knob shaft projecting into a slot in said bolt so as to engage a coin when in said transverse slot and cause the withdrawal of the bolt, and a spring for returning the bolt to normal position after an operation.

3. A coin controlled lock including a casing with a coin chute, front and rear knob shafts extending through said casing and having coin openings therethrough in registry with the coin chute, a reversible bolt between said shafts and having intersecting longitudinal and transverse slots therethrough, said transverse slot being normally in registry with said coin openings in said shafts, an extension from said front knob

- shaft projecting within the longitudinal slot in said bolt so as to engage a coin when in the bolt and cause the withdrawal of the bolt, a spring for returning the bolt to normal position, a plate within said casing having a coin opening therethrough normally in registry with said coin chute, a projection on said plate in position to be engaged by the coin as the bolt is withdrawn and move said plate and close the coin chute, and means on the rear knob shaft for engaging and withdrawing the bolt when said rear knob shaft is turned.
4. A coin controlled lock including a casing with a coin chute, front and rear knob shafts extending through said casing and having a coin opening therethrough in registry with the coin chute, a reversible bolt in said casing between said shafts and having longitudinal grooves in the faces adjacent the front and rear walls of said casing, a longitudinal slot therethrough parallel with said grooves and a transverse slot therethrough intersecting said longitudinal slot and grooves, and being normally in registry with said coin chute, a plate secured to said bolt within said longitudinal groove adjacent the rear wall of the casing and forming a continuous groove on the rear side of the bolt, an extension from said front knob shaft projecting within the longitudinal slot in said bolt so as to engage a coin when in the bolt and cause the withdrawal of the bolt, a spring for returning the bolt to normal position, a plate within said casing having a coin opening therethrough normally in registry with said coin chute, a projection on said plate in position to be engaged by the coin as the bolt is withdrawn and move said plate and close said coin chute, and means on the rear knob shaft for engaging and withdrawing the bolt when said rear knob shaft is turned.
5. A coin controlled lock including a casing with a coin opening therethrough, reversible front and rear knob shafts extending through said casing and having a coin opening therethrough, a coin chute within said casing in registry with the coin openings in said shafts, a reversible bolt in said casing normally extending beyond said casing and having a longitudinal groove in the faces adjacent the front and rear walls of said casing, a longitudinal slot therethrough parallel to said grooves and a transverse slot therethrough intersecting at right angles said longitudinal slot and said longitudinal grooves, said transverse slot being normally in registry with said coin slots, a plate secured to said bolt within said longitudinal groove adjacent the rear wall of the casing and forming a continuous slot on the rear side of the bolt, an extension from said front knob shaft projecting within the longitudinal slot in said bolt, whereby when a coin has been dropped into said transverse slot in the bolt and the front knob shaft turned, said extension will engage the coin and cause the withdrawal of the bolt, a spring for returning the bolt to normal position, a plate within said casing having a coin opening therethrough normally in registry with said coin opening in the casing and with said coin chute, a projection on said plate in position to be engaged by the coin as the bolt is withdrawn and move said plate and close the passageway to said coin chute, and means on the rear knob shaft for engaging and withdrawing the bolt when said rear knob shaft is turned.
6. A coin controlled lock including a casing with a coin opening therethrough, a coin chute within said casing, a rear knob shaft extending through the rear of said casing, a front knob shaft structure extending through said casing composed of an inner core member and a surrounding sleeve member having a slot in each end, said member having a coin slot therethrough, a pin in said core member lying within one of said slots, an arm on the sleeve member, a spring connection to said sleeve member for returning the same to normal position, a bolt in said casing normally extending beyond said casing and having a longitudinal groove in the faces adjacent the front and rear walls of said casing, a longitudinal slot therethrough parallel to said grooves and surrounding the arm on said front knob shaft sleeve, a transverse slot through said bolt intersecting said longitudinal slot and said longitudinal grooves, said transverse slot being normally in registry with said coin slots, a plate secured to said bolt within said longitudinal groove adjacent the rear wall of the casing and forming a continuous slot on the rear side of the bolt, said extension from said front shaft knob projecting within the longitudinal slot in said bolt, whereby when a coin has been dropped into said transverse slot in the bolt and the front knob shaft turned, said extension will engage the coin and cause the withdrawal of the bolt, a spring for returning the bolt to normal position, a plate within said casing having a coin opening therethrough normally in registry with said coin opening in the casing and with said coin chute, a projection on said plate in position to be engaged by the coin as the bolt is withdrawn and move said plate and close the passageway to said coin chute, and means on the rear knob shaft for engaging and withdrawing the bolt when said rear knob shaft is turned.
7. A coin controlled lock including a casing with a coin opening therethrough, a coin chute within said casing, a rear knob shaft extending through the rear of said casing, a front knob shaft structure extending through said casing and being composed of an inner core member and a surrounding

sleeve member having a slot in each end, a pin in said core member lying within one of said slots, an arm on the sleeve member, a spring connection to said sleeve member 5 for returning the same to normal position, a bolt in said casing normally extending beyond said casing and having a longitudinal groove in the faces adjacent the front and rear walls of said casing, a longitudinal slot therethrough parallel to said grooves and surrounding the arm on said front knob shaft sleeve, a transverse slot through said bolt intersecting said longitudinal slot and said longitudinal groove, 10 said transverse slot being normally in registry with said coin slots, a plate secured to said bolt within said longitudinal groove adjacent the rear wall of the casing and forming a continuous slot on the rear side 15 of the bolt, an extension from said front shaft knob projecting within the longitudinal slot in said bolt, whereby when a coin has been dropped into said transverse slot from the bolt and the front knob shaft 20 turned, said extension will engage the coin and cause the withdrawal of the bolt, a spring for returning the bolt to normal position, a reversible plate within said casing having coin openings therethrough, one 25 of said coin openings being normally in registry with said coin opening in the casing and with said coin chute, a plate secured to said slot closing plate and lying within the longitudinal groove of said bolt 30 adjacent the front wall of the casing and having the central portion thereof cut away, a downward and inward inclined portion on either side of said central portion, an inward projection on the end of said inner 35 plate and adjacent said inclined portion, one of said inclined portions being adapted to normally lie in registry with the transverse slot through said bolt and prevent the passage of the coin therethrough, said end projection being adapted to be engaged by the coin as the bolt is withdrawn under the casing of the front knob shaft and move 40 said slot closing plate to one side and close the entrance to said coin chute, and a rearwardly extending lug on said slot closing plate adapted to be engaged by the rear knob shaft as said knob shaft is turned to move said slot closing plate to normal position.

8. A four way coin controlled lock including a casing with a coin opening therethrough, a reversible front and rear knob shaft extending through said casing, a reversible and invertible bolt in said casing normally extending beyond said casing and 45 adapted to be withdrawn when said rear knob shaft is turned and by said front knob when turned after a coin has been inserted through said opening, and a reversible slot closing plate adapted to be moved to closing 50 position by the coin under the action of said front knob shaft and returned to normal position by said rear knob shaft, whereby said lock may be installed upon either lateral edge of a door swinging either in 55 or out.

In witness whereof, I have hereunto affixed my signature in the presence of the witnesses herein named.

GEORGE G. F. BOSWELL.
